UNITED STATES PATENT OFFICE.

JOHN TAYLOR, OF SALT LAKE CITY, UTAH.

FUEL-FEEDING MECHANISM FOR COAL-DUST FURNACES.

Application filed June 13, 1921. Serial No. 477,207.

To all whom it may concern:

Be it known that I, JOHN TAYLOR, a citizen of the United States of America, residing at Salt Lake City, in the county of Salt Lake and State of Utah, have invented certain new and useful Improvements in Fuel-Feeding Mechanism for Coal-Dust Furnaces, of which the following is a specification.

10 This invention relates to fuel feeding mechanism for coal dust furnaces. A Patent No. 1,373,776 of April 5, 1921, was granted to me for mechanism of the general character of that shown in this application. However, 15 as this description proceeds, it will be seen that many refinements and improvements over the structure of the aforesaid patent are embodied in this my improved apparatus.

The invention includes among its objects 20 the provision of a simple and economical construction by means of which fine fuel, such as powdered coal may be fed, in suspension, along with a column of air, into a fuel supply pipe leading to the combustion chamber of a furnace (not shown). Furnaces for burning fine fuel in suspension are well known in the art and this application relates 25 particularly to the means for feeding such fine fuel rather than to any particular type 30 of furnace, the device being applicable to furnaces of different kinds.

It is also an object of the invention to provide means for uniformly crushing the coal to insure against particles of more than a 35 given size being fed through the blast fans, and to vary the degree of fineness of the coal at will, and also to provide means for varying the proportion between the coal dust and the air.

40 Further objects and advantages of the invention will be set forth in the detailed description which follows.

In the accompanying drawings:

Fig. 1 is a plan view of that part of the 45 feeding mechanism which underlies the coal bin;

Fig. 2 is a side elevation of the construction illustrated in Fig. 1;

Fig. 3 is a plan view of the lower part of 50 the mechanism illustrated in Fig. 2;

Fig. 4 is a detail view of a spiral conveyor hereinafter described;

Fig. 5 is a side elevation of the fuel feeding mechanism with the coal bin in section;

Fig. 6 is a view partly in section and partly in plan of the fan end of the feeding mechanism;

Fig. 7 is a sectional view upon line 7—7 of Fig. 8;

Fig. 8 is a sectional view upon line 8—8 of Fig. 7; and

Fig. 9 is a sectional view illustrating a "two stage fan."

Like numerals designate corresponding parts throughout the several figures of the drawings.

In the drawings 5 designates a coal bin having an opening 6 in its bottom which registers with an opening 7 formed in the upper half of a casing 8. This casing is 70 provided with perforated ears 9 through which bolts 10 may be passed for the purpose of bolting the casing to the under side of the coal bin. A manually operable slide 11 is adapted to restrict the size of the opening 7 to any desired extent, or to completely close the same, at will. This slide is operable in a channel 12 and moves beneath a keeper 13, see Fig. 1. The lower half 8^a of the casing is secured to the upper half 80 thereof by nuts 14 which may be threaded upon the lower ends of the bolts 10, or may be threaded upon separate screws 15, it being apparent that many ways of securing these parts together will readily suggest 85 themselves to the mechanic. The interior of the casing 8 is spirally grooved or rifled, as indicated at 16, and a spiral conveyor 17, see Fig. 4, operates in this casing. This spiral conveyor differs radically from ordinary spiral conveyors, in that it comprises two distinct helical grooves, one of which increases in pitch from the front to the rear end of the conveyor and the other of which decreases in pitch. The result is that one 90

groove, viz, groove 18 is of considerable capacity at the start and gradually decreases in capacity toward the right until it merges into nothingness at about the point 18^a. The other groove, which is substantially the reverse of the first, begins at 19^a and gradually increases in capacity forming a groove 19, which extends to the terminal or right hand end of the conveyor and beyond the 100

point where the groove 18 vanishes. Furthermore, it may here be noted that the conveyor as a whole flares, being of larger diameter at its right hand end than at its left hand end, and the same thing is true with respect to the interior of the chamber 8, as will be apparent from a careful inspection of Fig. 3. It is the action of the rib 18^b acting in conjunction with the grooves 16 10 which acts to grind the coal to a uniform degree of fineness, and this degree of fineness may be varied by shifting the conveyor endwise in the casing 8. This is accomplished by means of a rod 20 which is pivoted at 21 to a lever 22. The lever 22 is pivoted, in turn at 23 to a bracket 24 of the casing 8. The lever 22 carries a pin 25 which enters an annular groove 26, see Fig. 4, in the shaft of the conveyor. Thus endwise movement of the rod 20 will shift the conveyor endwise without interfering with the rotative movement of the conveyor. The right hand end of the rod 20 carries a pin 21^a the lower end of which is adapted 15 to be inserted in any one of the openings 22^a by means of which the conveyor may be held in its adjusted position. A coal delivery pipe 23^a leads from the left hand end of the casing 8 and coal is fed through this pipe 20 by the conveyor 17, the coal initially entering the grooves 18 and remaining trapped therein until it is crushed to such a degree of fineness that it will pass about or beneath the rib 18^b from the groove 18 to the groove 35 19. In other words, only coal which has been crushed to the desired degree of fineness can enter the groove 19, and it is this groove which extends to the delivery point 24^a, where the finely powdered fuel is discharged into a downwardly directed channel 25^a (see Fig. 7).

The right hand end of the conveyor shaft 17^a carries a toothed wheel 26^a, and this toothed wheel is engaged by a worm 27 that 45 is mounted upon a transverse shaft 28. The shaft 28 carries a large pulley 29 that is driven by a belt 30 and a motor shaft 31. The belt may be tightened at any time by merely adjusting the housing 32, shaft 28 50 and pulley 29 toward the right by means of the screws 33 slots 34 and screw 34^a. The motor 35 of which 31 constitutes the main shaft is concentrically disposed with relation to a fan casing 36. The fan 37 is 55 mounted directly upon the motor shaft and a fuel feeding wheel 38 is likewise mounted directly upon said shaft and controls the passage of fuel from the channel 25^a into the fan casing proper. A fuel discharge pipe 60 39 leads from the fan casing to any desired point of discharge, such, for example, as the combustion chamber of a furnace.

The fan receives its air supply through an opening 40 that is controlled by a door 65 41. This door is hinged at 42 and a pivoted

lever 43 carried by said door is operated by a chain 44. When the chain is slackened or lowered, the weight 45 carried by the lever acts to open the door. In order to insure that this door will always be open when the 70 motor is started, I may associate with the chain 44 a controlling switch that is included in the motor line. Such an arrangement is diagrammatically shown in Fig. 8. Wires 75 46 and 47 designate the motor leads having a break included therein which may be closed by bringing the inner end 49 of a lever 50 into engagement with the contact points 51 and 52. This lever is pivoted at 80 53 and its outer end engages with one of the links of the chains 44. Thus when the chain descends to open the door 41, the inner end of the lever 50 rises and completes the circuit of the motor and the motor cannot be started 85 until this is done.

Furthermore when the motor is stopped by upward movement of the chain and lever 50, the door will be closed and this will prevent leakage of air through fuel feeding pipe 39 through the combustion chamber, when 90 the fuel feeding apparatus is idle and which leakage of air would otherwise undesirably cool off the combustion chamber.

In Fig. 9 I have illustrated a two stage fan which may be employed advantageously 95 where high pressure is desired. The parts, in the main, are the same as those employed in Fig. 8, and the same reference characters have been applied. The structure differs from that illustrated in Fig. 8 in that two sets of blades 37^a, 37^b, have been illustrated constituting, a two stage fan. Two separate outlets 55 and 56 are provided and if the outlet 55 be separately connected to a combustion chamber and if the outlet 56 be likewise connected to said combustion chamber, it is manifest that pure air free of fuel in 100 suspension may be delivered to the combustion chamber from the outlet 55 or that by closing the outlet 55 all of the air may be delivered through 56, as high pressure air, with the fuel in suspension therein.

Whether a single stage fan, such as is illustrated in Fig. 8, be employed or whether a two stage fan, such as is illustrated in Fig. 9, be employed, it is desirable to prevent air from leaking back past the conveyor to the coal bin, since this air would support combustion if a fire got started in the coal bin. Therefore, I provide a port 25^b through 115 which air may enter and pass downwardly past the fuel feeding wheel setting up a circulation, as indicated by arrow C, to draw air away from conveyor 17. In Fig. 9 a port 57 leads from a point adjacent the discharge end of the conveyor around to the intake side of the fan and this prevents the passage of air back past the conveyor into the coal bin.

It is to be understood that the invention is 13

not limited to the precise construction set forth but that it includes within its purview whatever changes fairly come within either the terms or the spirit of the appended 5 claims.

Having described my invention, what I claim is:

1. In a device of the character described the combination with a coal bin, of a blast 10 apparatus and a fuel feeding and comminuting means extending between the coal bin and the blast apparatus and receiving the coal from the coal bin and delivering it to the blast apparatus to be discharged by the 15 latter into a furnace, said fuel feeding and comminuting means comprising a casing connected at one end to the coal bin and at the other end to the blast apparatus and a spiral conveyor mounted for rotation in said 20 casing, said conveyor having a fuel receiving groove and a fuel discharge groove formed therein, said grooves interlapping axially, and said grooves being separated by spiral walls which are so proportioned and ar- 25 ranged with respect to the casing as to permit the passage of powdered fuel from the fuel receiving groove to the fuel discharge groove when said fuel has been crushed to a predetermined degree of fineness.
- 30 2. A structure as recited in claim 1 wherein said spiral conveyor flares in its length and means for adjusting it lengthwise in combination with the casing in which it operates, such lengthwise adjustment varying

the spacing of the periphery of the conveyor 35 from the wall of its casing to determine the degree of fineness to which the fuel must be crushed before it passes from the fuel receiv- ing groove to the delivery groove.

3. The combination with a coal bin, of a 40 casing having a receiving end and a dis- charge end, said casing flaring from its re- ceiving end to its discharge end and said casing having a spiral groove formed in its walls which gradually diminishes in depth 45 from the receiving end of the casing toward the discharge end thereof, and a spiral con-veyor mounted for rotation in said casing, said conveyor flaring toward the discharge end of said casing, said conveyor having two 50 spiral grooves formed therein which over- lap axially, one of said grooves constituting a receiving groove which is of large capacity at the receiving end of the conveyor and di- minishes in capacity toward the discharge 55 end of the conveyor and the other of said grooves being of small capacity at that end of the conveyor toward the coal bin and in- creasing in capacity toward the discharge 60 end of the casing the last named groove ex- tending further along the conveyor than the first named groove.

In testimony whereof I affix my signature in the presence of two witnesses.

JOHN TAYLOR.
